DUST DEFLECTOR

George S. Kelley, Mount Vernon, N. Y., assignor
to Kadco Corporation, New York, N. Y., a cor-
poration of New York

Application September 22, 1938, Serial No. 231,155

3 Claims. (Cl. 255—50)

This invention relates to dust deflectors, and more particularly to dust deflectors adapted for use in connection with rock drilling apparatus equipped with means for ejecting the dust from the holes being drilled.

This invention is an improvement of the subject matter of my Patent No. 2,055,768, issued September 29, 1936, and its principal object is to improve the operation and effectiveness of apparatus of the general character described in that patent.

More particularly, it is an object of this invention to prevent the escape of dust during that period in which a drill hole is being started.

Still another object of the invention is to prevent, in a relatively simple and effective manner, the escape of dust and rock particles at the upper end of the dust deflector.

Other objects of the invention will be in part obvious and in part pointed out hereinafter.

In the drawing accompanying this specification, and in which similar reference characters refer to similar parts,

Figure 1 is an elevation in section of a preferred embodiment of the invention as applied to a rock drilling mechanism including the drill steel, portions of the rock drill being in section.

Figure 2 is a transverse view taken through the lower part of the deflector on line 2—2 in Figure 1, looking in the direction of the arrows, and

Figure 3 is a vertical section of the lower part of the dust deflector and its skirt, showing the deflector inserted in a drill hole.

Referring more particularly to the drawing, the dust deflector consists generally of a tubular member 10 through which is adapted to be inserted a drill steel 12, there being formed preferably integrally with the tubular member 10 an angularly disposed extension 14 through which the removed dust is adapted to pass. Tubular member 10 is adapted to slide into the hole being drilled as shown in Figure 3, and to this end its diameter is preferably less than that of the bit 16 of the drill steel 12.

As is described in the patent above referred to, when the hole is being started as at 18, tubular portion 10 rests on the bit 16 and enters the hole as the latter deepens. In practice it has been found that the bit 16 will obstruct the hole in the tube 10 so that the suction at that point, as will be hereinafter described, will not be sufficient to collect all the cuttings generated at the face of the bit 16. To obviate this difficulty, a skirt is provided on the tubular portion 10 fitting

tightly at a smaller diameter 20 and flaring out in a generally conical shape as at 22. This skirt may be of any suitable flexible material and is preferably relatively limp, so as not to obstruct the dropping of the tubular member 10 in the hole 18 as the drilling progresses. The skirt 22 confines the dust formed by the bit 16 so that the dust will be withdrawn by way of the tube 10. Obstruction to the passage of dust laden air into the tube 10 at its extreme lower end is 10 counteracted by provision of orifices, in this instance two, as at 24, sufficiently wide to enable suction in the tube 10 to evacuate the space within the skirt 22. The upper end 26 of tube 10 is open and is adapted to permit atmospheric air to 15 enter as it will.

As has been described in the patent above referred to, the angularly disposed conduit 14 is attached to a hose 28 leading to suitable suction apparatus (not shown), but adapted to withdraw 20 air in quantities substantially greater than introduced into the drill hole 18 through the center hole 30 of the drill steel 12. Thus, the evacuating apparatus is arranged to draw air into the tube 10, not only through the hole 18, but also at the 25 upper end 26, the latter forming an air seal by means of a current of air flowing counter to the direction of particles blown out of the hole by the usual stream of cleansing air introduced through the drill steel.

In order to facilitate the passage of dust into the extension 14, a baffle 32 is provided extending into the path of the stream of air-laden dust passing upwardly in the tube 10, and is adapted to guide in a smooth path, such dust-laden air to the hose 28. Means are provided by this invention to insure that the dust laden stream will be deflected into the conduit 14 and, to this end, an air inlet 34 is provided in the tube 10, slightly below the lower edge of deflector 32. Air entering at the opening 34 provides a blast of sufficient magnitude to convey the entire batch of dust-laden air sidewise to be engaged by the deflector 32.

As shown in Figure 1, drill steel 12 is, in this instance, of the lugged variety, having projections 36 to engage a chuck sleeve 38, suitably mounted in the front-head 40 of a pneumatic rock drill 42 of any suitable design.

In operation, the drill steel 12 is slipped through the front end of the tube 10 of the dust deflector shank end first, the lugs 36 being of a diameter less than the internal diameter of the tube 10. The steel 12 is then inserted into the front end of the chuck 38 of the rock drill 42 and

the bit 16 is positioned on the rock bed 44 at the point where it is desired to drill a hole 18. The deflector forms, at this stage, a guide for the bit 16, inasmuch as the drill operator may hold the 5 drill steel steady by pressure of his foot against the skirt 22 or the tube 10.

Under usual circumstances, the evacuating apparatus attached to the hose 28 is continuously operated so that chips and dust generated by the 10 bit 16, as the hole 18 is being started or "collared" pass into the interior of the skirt 22 and are withdrawn either at the lower end of the tube 10 beyond the wings of the bit 16, or through the 15 holes 24. Dispersion of the dust formed by the bit 16 is increased by the introduction of cleansing air passing from the drill through the center hole 30 of the hollow drill steel 12, for the purpose of keeping the rock face clear of cuttings. The column of dust and cuttings passing upwardly through the tube 10 is met as it approaches the baffle 32 by a blast of air introduced 20 at the aperture 34 due to suction in the direction of the hose 28. The column of dust-laden air is thus deflected into the sidewise extending conduit 14 and led to a suitable disposal means (not shown).

In addition to the blast of deflector air entering at the aperture 34 a further counter current stream of air, also passing to the conduit 14, is 30 introduced at the upper end 26 of tube 10, which turns back any particles which may have had sufficient momentum to carry them through the blast at aperture 34.

As drilling continues, deepening the hole 18 as 35 shown in Figure 3, the skirt 22 collapses, preferably, from the weight of the deflector or by pressure applied. Thereupon, the tube 10 drops into the hole 18 and the skirt is temporarily inoperative as being unnecessary until another hole is 40 to be collared. The tube 10 of the deflector is adapted to remain in the hole, as shown in Figure 3, during all further drilling operations in that hole.

Thus are accomplished among others, the objects hereinbefore referred to.

The present invention has been found to be a highly efficient device for effecting the positive and efficient removal of dust from both the drill

hole and the vicinity of the drilling operation. As will be readily appreciated, it is of simple construction, and so designed that it may be conveniently and cheaply manufactured.

I claim:

1. A dust deflector comprising a substantially straight tubular portion adapted to receive a drill steel and to fit into a drill hole formed thereby, an angularly disposed conduit connected with said tubular portion intermediate, a baffle in said conduit at its juncture with the tubular portion for guiding dust-laden air into said conduit from said tubular portion, and an aperture intermediate the ends of said tubular portion oppositely disposed therein with respect to said conduit to direct a jet of air in the direction thereof.

2. A dust deflector comprising a substantially straight tubular portion adapted to receive a drill steel and to fit into a drill hole formed thereby, 20 an angularly disposed conduit connected with said tubular portion, a baffle in said conduit at its juncture with the tubular portion for guiding dust-laden air into said conduit from said tubular portion, said tubular portion being provided with 25 an aperture oppositely disposed therein with respect to said angularly disposed conduit to direct a jet of air into the said conduit, and a flexible skirt on said tubular portion adapted to overlie the drill hole.

3. A dust deflector comprising a substantially straight tubular portion adapted to receive a drill steel and to fit into the drill hole formed thereby, an angularly disposed conduit connected with said tubular portion, a baffle in said conduit at 35 its juncture with the tubular portion for guiding dust-laden air into said conduit from said tubular portion, and an aperture intermediate the ends of said tubular portion oppositely disposed therein with respect to said angularly disposed conduit to direct a jet of air in the direction thereof, a flexible skirt on the tubular portion overlying the drill hole adapted to collapse as the tubular portion enters the drill hole and lateral disposed 40 apertures in said tubular portion communicating 45 with the space within said skirt.

GEORGE S. KELLEY.
